UNITED STATES PATENT OFFICE.

FREDERICK A. SMALL, OF BLUE ISLAND, ILLINOIS.

ROTARY ENGINE.

SPECIFICATION forming part of Letters Patent No. 552,646, dated January 7, 1896.

Application filed September 5, 1894. Renewed June 19, 1895. Serial No. 553,369. (No model.)

To all whom it may concern:

Be it known that I, FREDERICK A. SMALL, a citizen of the United States, residing at Blue Island, in the county of Cook and State 5 of Illinois, have invented a new and useful Improvement in Rotary Engines, of which the following is a specification.

My invention relates to improvements in rotary steam-engines of the class in which a 10 hub portion is surrounded by a rotary shell or wheel containing an annular expansion-chamber and provided with valves against which the steam expands to propel the shell or the hub, whichever may constitute the rotary portion.

My object is to provide an engine of the above class of generally improved construction in which the moving parts shall be exposed continuously to steam-pressure, which 20 shall be particularly economical in the consumption of steam, and which shall be of a simple and durable construction and every way desirable for its purpose.

In the drawings, Figure 1 is a vertical longitudinal and central section of my improved engine, the section being taken on line 1 of Fig. 2; Fig. 2, a section taken on line 2 2 of Fig. 1 and viewed in the direction of the arrows; Figs. 3, 4 and 5, enlarged sections 30 taken, respectively, on lines 3, 4 and 5 of Fig. 1 and viewed in the direction of the arrows; Fig. 6, an enlarged broken section taken on line 6 of Fig. 2, viewed in the direction of the arrow, and illustrating details of construction 35 of the governor and cut-off mechanisms; Figs. 7 and 8, details of construction of the cut-off actuating mechanism; Fig. 9, a diagram of one of four similar stationary and annular cams which work the valves in the expansion-chamber; Fig. 10, an elevation of two rotary rings at one side of the rotary wheel, forming 40 part of the valve-sliding mechanism, two similar rings being on the opposite side of the wheel; Figs. 11, 12 and 13, sections of a stationary steam-chest taken on lines 11, 12 and 13 of Fig. 3 and viewed in the direction 45 of the arrows; Fig. 14, a broken plan view of one of the movable cut-offs; Fig. 15, a broken section of the stationary hub or steam-chest 50 portion taken on line 15 of Fig. 3 and viewed in the direction of the arrow; Fig. 16, a broken section of a split-ring segment and mov-

able valve, forming details of the construction; and Fig. 17, a broken view showing the upper end portion of an outer standard in 55 which the stationary shaft of the engine is secured against rotation.

The engine illustrated in the figures is a double engine containing two steam-chests, two expansion-chambers and two sets of 60 valves and cut-offs of exactly similar construction, whereby the power of the engine is doubled. The shaft and parts fixed thereon, in the figures, remain stationary while the parts surrounding them rotate; but if desired, as hereinafter explained, this may be reversed to cause the shaft and attendant parts to rotate while the surrounding parts remain stationary.

A is a base provided at opposite end portions with inner standards A' A' and outer standards A² A².

B is a shaft which is bored from opposite ends to form passages t and s divided from each other by an abutment x where the shaft 75 is solid.

It will be understood that the shaft is bored from opposite ends to a point near the center, leaving the solid portion x at the center, and this is the preferred construction, though, 80 if desired, the shaft may be made hollow all the way through and provided at its center with a plug to form the abutment x.

At the inner end of the passage t is a radial opening t', and at the inner end of the passage s is a radial opening s'. Along its central portion the shaft B is threaded, as indicated at x' in Fig. 1. Each standard A² is provided in its outer side with a recess r, and at the center of the recess with an opening r'. 90 Fitting in the recess r is a block or frame r², which fills the recess from the lower to the upper side thereof, but is slightly less in width than the width of the said recess. (See Fig. 17.) When the frame r² is placed in the recess it may be slid to a limited extent from right to left, but has no up-and-down play. Fitting in the frame r² is a block or plate r³ corresponding in width to the width of the opening of the frame r², but of a height somewhat less than that of the said opening. Thus the plate r³ has play to a limited extent in the vertical direction in the frame r², but no independent play from right to left. The plate 100

r^3 has a central opening r^4 to fit over the hollow shaft B, and the shaft and plate r^3 are coincidently grooved to form a keyway to receive a key r^5 . The standards A² with their frames r^2 and plates r^3 operate to hold the shaft B secure against turning to the slightest extent on its axis, but will permit limited play of the shaft in the vertical and horizontal directions to compensate for wear of the shell-trunnions in their bearings, hereinafter described.

On the threaded portion a' of the shaft B is a stationary hub C. The body portion of the hub C may be a solid casting and is formed at one end portion with a segmental chamber e , Fig. 4, and at its opposite end portion with a segmental chamber q , Fig. 5. The arrows in the figures indicate the direction of flow of the steam, the chamber q being the steam-inlet chamber for both steam-chests and the chamber e the exhaust-chamber for both the expansion-chambers. The segmental chambers e and q are of the relative sizes and occupy the relative positions indicated in Figs. 4 and 5. At one end of the chamber q is an opening q' which registers with the opening t' in the shaft, and in the chamber e , at the center of the latter, is an opening e' which registers with the opening s' in the shaft. Extending from the chamber q out through the adjacent end of the body portion of the hub is an opening q^2 , and extending from the chamber q through the body portion of the hub to the opposite end thereof is a passage q^3 . Extending from the chamber e out through the adjacent end of the body portion of the hub is an opening e^2 , and extending from the chamber e through the body portion of the hub to the opposite end of the latter is an opening e^3 . Fitting into a recess y , Fig. 15, in one end of the body portion of the hub C at the openings q^3 e^2 and forming practically an integral part of the hub is a chambered head or casting p held in place by bolts p' . (See Figs. 3 and 15.) At and for a little distance radially beyond the body portion of the hub the casting p is narrow in the direction lengthwise of the shaft and affords a hollow neck portion p^2 . Beyond the neck portion the casting widens into a head p^3 , rectangular in cross-section and formed in its face with a dovetail recess p^4 . (See Fig. 3.) The casting p has a chamber or passage p^5 , Fig. 3, which is open at the outer circumference and forms the inlet-mouth of the passage or opening e^2 and a chamber or passage p^6 in open communication with the passage q^3 and extending through the neck p^2 and head p^3 and out through the dovetail face p^4 .

Fitting into the dovetail face p^4 is a hollow segmental arm or casting n rectangular in cross-section and of the same width as the part p^3 . Fastened against the opposite end of the body portion of the hub is a chambered head or casting m , in every way like the part p and secured to the hub in the same manner. It

has a chamber or passage corresponding with the chamber p^5 and forming the mouth of the passage e^3 , a chamber corresponding with the chamber p^6 and in open communication with the opening q^2 , and a segmental arm m' fastened to it by the dovetail joint n^2 . A more detailed description of the arms n m' will be given later on. The outer circumference of the hub affords annular bearing-surfaces x^2 x^3 , Fig. 1.

D is a shell which may be an annular rotary wheel containing the steam-cylinders or expansion-chambers. It is in two parts D' D², secured together by bolts l and presenting on their outer circumference a drive-pulley l' . In the tops of the standards A' are bearings k for hollow trunnions D³ D³. Each section D' D² is provided with a laterally-extending annular flange l^2 , secured at its free edge to a disk D⁴, formed integral with the respective trunnion D³. In the section D' is an annular expansion-chamber E and in the section D² is an annular expansion-chamber E', both expansion-chambers being rectangular in cross-section. At the chambers E E' the wheel D is formed with annular bearing-surfaces x^3 x^2 , which rotate upon the bearing-surfaces x^2 of the hub, and longitudinally and centrally of the expansion-chambers, being midway between the bearing-surfaces x^3 , are continuous annular inner peripheral slots or openings i . Between the disks D⁴ and body portions of the wheel D and hub C at opposite ends of the latter are chambers F F', the outer annular walls of which are the flanges l^2 , and in the disks D⁴ are occasional openings y' , through which access may be had to the chambers F F'. Fitting over the openings y' are removable plates y^2 , which, when in place, tightly close the said openings. In the chambers F F' and rigidly secured to the stationary shaft B are outer annular cams h and inner annular cams h' concentric with each other. The cams h h' are alike and are disposed the same with relation to the shaft—that is to say, the projecting surfaces h^2 are opposite each other across the hub in the same plane, and the depressed surfaces h^3 are also opposite each other in the same plane. The inner cams h' are both disposed the same with relation to the cam h , whereby their projecting surfaces h^2 are opposite each other across the hub and their depressed surfaces h^3 are in the same relation.

Extending through the wheel D parallel with the shaft B and equidistant from each other are four openings g at the outer circumferential walls of the chamber E E' and just large enough to receive longitudinally-reciprocating rods g' . Arranged in a circle concentric with and around a circle drawn through the openings g are openings f in radial line with the openings g , respectively, and just large enough to receive reciprocating rods f' . The circular plane of the openings g corresponds with that of the inner cams h' , and the circular plane of the openings f corresponds with the plane of the outer cams h . At the centers

of the openings f are cylindrical longitudinally-extending chambers f^2 , in which pistons f^3 , fixed upon the rods f' , slide. In the movement of the rods f , as hereinafter explained, 5 the slight resistance to movement of the pistons f^3 in the chamber f^2 , due to air-compression, will tend to cushion the rods.

In the chamber F is a yoke or ring d . (Shown in detail in Fig. 10.) It is provided with two 10 radial outwardly-extending diametrically-opposed arms d' , to each of which is fastened a radially-extending plate d^2 , having two openings g^3 f^4 , respectively. The rod f' in the upper opening f , as it appears in Fig. 1, passes 15 near one end in the chamber F, through the opening f^4 in one plate d^2 and the rod is rigidly secured to the plate by jam-nuts d^3 . At its adjacent end the same rod f' carries a head f^4 , in which is mounted an antifriction-wheel f^5 , which runs upon the track afforded 20 by the adjacent outer cam h . The rod g' , adjacent to the said rod f' , extends at its end through the opening g^2 of the same plate d^2 ; also in the chamber F and passing through 25 the opening g^2 of the plate d^2 is the end portion of the rod g' , which is diametrically opposed to the last-mentioned rod g' . The rod g' in question appears below the shaft in Fig. 1 and is provided beyond the plate d^2 with a 30 head g^2 , having an antifriction-wheel g^4 , which runs upon the track afforded by the inner cam h' .

In the chamber F' is a yoke d^4 , (in all respects like the yoke d^4 in Fig. 10, but turned 35 a half-revolution with relation thereto,) the inner circumference of which is of a diameter approximating the distance from tip to tip of the plates d^2 on the yoke d , whereby the yoke describes a circle outside a circle drawn 40 through the rods f' . At diametrically-opposite points the yoke d^4 is provided with radially inwardly-projecting lugs d^5 . The rod f' , referred to above as the upper rod in Fig. 1 and which carries the friction-wheel f^5 in 45 the chamber F, extends in the chamber F' through an opening d^6 in one lug d^5 of the yoke d^4 , referred to, and the adjacent rod g' extends through an opening d^7 in the same lug d^5 and carries a head g^3 , provided with 50 an antifriction-wheel g^4 riding upon the cam h' in the chamber F'. The said rods f' and g' are secured rigidly to the yokes d^4 at the said openings d^6 d^7 by means of jam-nuts d^3 . The end of the rod g' diametrically opposite the one described and which appears 55 below the shaft in Fig. 1, where it projects into the chamber F', is secured in the opening d^7 of the lug d^5 diametrically opposite the lug d^5 described, and the adjacent rod f' 60 passes in the chamber F' through the opening d^6 in the same lug, beyond which it carries a head f^4 provided with an antifriction-wheel f^5 riding upon the outer cam h in the chamber F'. 65 From the foregoing explanation it will be understood that the yoke d in the chamber F and the yoke d^4 in the chamber F' are tied

together by two pairs of diametrically-opposed longitudinally-sliding rods $f' g'$; that one rod f' has a wheel f^5 which travels on the outer cam h in the chamber F, and the other rod f' has a wheel f^5 which travels upon the outer cam h in the chamber F'; that the rod g' adjacent to the first said rod f' has a wheel g^4 which travels upon the inner cam h' in the chamber F', and that the other rod g' has a friction-wheel g^4 which travels upon the inner cam h' in the chamber F. Thus in the rotation of the wheel D, as hereinafter described, the whole shifting frame described, 70 consisting of the yoke d in the chamber F, the yoke d^4 in the chamber F', and the rods $f' g'$, which connect at opposite ends with the said yokes, is slid to the left by the cams $h h'$ in the chamber F and remains in that position during half the revolution, and that the frame is then slid by the other cams $h h'$ in the chamber F' to the right and remains in that position during the other half of the revolution. At the sides of the chambers E E', 75 in direct radial line with the openings $f g$, are narrow slits or recesses g^5 , which extend laterally of the chambers E E' in the direction longitudinally of the shaft B and intersect the said chambers and adjacent openings 80 g . On the rods g' are flat plates or valves E^2 for the chamber E and similar valves E^3 for the chamber E'. 85

It will be noticed that at one side of the wheel (the upper portion in Fig. 1) the slits g^5 are between the chambers E E' and that at the opposite side of the wheel the slits or recesses g^5 are at the outer sides of the chambers E E'. The valves E^2 E^3 and recesses g are, approximately, of the same size, so that 90 the valves will just fit the said recesses when slipped into them. The valves when slid from the recesses across the respective chambers fit into grooves w , which, with the recesses, envelop the four edges of the valves, 95 causing the valves to completely close the chambers at those points to afford steam-tight abutments.

The valves E^2 E^3 (shown at the upper sides of the wheel in Fig. 1) are comparatively close 100 together, so that in the sliding of the rod g' to which they are secured in one direction the valve E^3 moves into its recess g^5 out of the chamber E', and at the same time the adjacent valve E^2 moves out of its recess g^5 across 105 the chamber E. The valves E^2 E^3 at the lower side of the wheel in Fig. 1 are secured comparatively far apart on the adjacent rod g' , so that while they move in the same directions and simultaneously with the upper said 110 valves E^2 E^3 their action is the opposite. Thus, for example, as shown in Fig. 1, while 115 moved to the right the upper valve E^2 closes the chamber E the lower valve E^2 when moved to the right opens the chamber E, and 120 while the upper valve E^3 when moved to the right opens the chamber E' the lower valve E^3 when moved to the right closes the chamber E'. 125 When the valves are moved to the 130

left, the upper valve E^2 will open the chamber E , and the lower valve E^3 will close the chamber E , while the upper valve E^3 will close the chamber E' , and the lower valve E^2 will open the chamber E' .

It is to be understood that I use the term "closes the chamber" when the valve extends across and forms an abutment therein, and "opens the chamber" when the valve 10 slides therefrom laterally into its recess.

In the chamber F' is ring or yoke d , in every respect like the ring or yoke d in the chamber F hitherto described, and in the chamber F is a ring or yoke d^4 in every way like the ring 15 or yoke d^4 in the chamber F' and illustrated in Fig. 1. These yokes are connected to and tied together by the other two pairs of rods $f' g'$, which extend in a plane at right angles to the plane of the rods described and carry 20 valves $E^2 E^3$, which are operated in exactly the same way by movement of antifriction-wheels on the rods against the cams $h h'$. It will be understood that in the revolution of the wheel the two sets of valves move alternately—that is to say, each set is moved once with each half-revolution of the wheel, so that there is a movement of valves across each 25 chamber four times with each revolution. The two sets of valves are timed to move 30 across and away from the chambers to open and close the latter, as hereinafter explained.

The arms $n n'$ are formed exactly alike, so that a description of one will explain the construction of the other. The butt-end portion 35 n' of the arm n is of approximately the same size in cross-section as the chamber E' , and the butt-end portion m^3 of the arm m' is of approximately the same size in cross-section 40 as the chamber E . In the part n' , at the locations shown, are recesses n^2 , which are in the outer faces of the part. Extending from the interior or chamber n^3 at the said recesses are openings n^4 , one each at the top and bottom and two on each side, as shown in Fig. 45

11. The openings n^4 are made flaring at their ends toward the recesses n^2 , and fitting into them are pins n^5 . The pins n^5 fit closely but loosely in the openings n^4 and are of a length corresponding with the lengths of the said 50 openings. Fitting in the side recesses n^2 are packing-strips $n^6 n^6$ and fitting in the top and bottom recesses are packing-strips $n^7 n^7$. The outer surfaces of the strips $n^6 n^7$ are normally flush with the outer surface of the part n' of the arm, which, as before stated, approximately fills out the chamber E' . The pressure of steam in the chamber n^3 , as hereinafter described, bears against the inner ends of the pins n^5 , forcing them outward against the strips $n^6 n^7$, to press the latter firmly against the inner surfaces of the chamber E' to insure a steam-tight packing. As indicated at the arms m' in Fig. 3, the ends of the friction or packing strips n^7 are formed into tongues to 65 fit into sockets or grooves in the ends of the strips n^6 to prevent separation of the strips at their ends when expanded or forced out-

ward by the force of the steam in the chamber n^3 .

The arm throughout is of the same width 70 in the direction longitudinally of the shaft B , so that throughout its entire extent it approximately fills out the chamber E' in that direction. From points forming inner and outer shoulders or abutments n^8 the arm is 75 reduced in thickness in the direction radially of the wheel. Near the outer edge of the narrow part of the arm n , on each side thereof, is a steam-outlet opening n^9 , elongated in the direction of the length of the arm and of segmental form corresponding with the shape of the arm. The opening n^9 extends nearly the full length of the narrowed part of the arm n , as indicated by full and dotted lines in Fig. 2. The forward end portion of each opening 80 n^9 is closed by a cap-plate n^{10} , screwed upon the side of the arm in a recess formed therein for the purpose, and the said plate n^{10} extends flush with the surface of the arm, all as shown in Fig. 12. The purpose of this plate 85 n^{10} is to cause the forward portion of the opening n^9 to afford the guide for a cut-off, actuated by a governor, which will all be hereinafter described.

In each side wall of the chamber E equidistant 90 from each other are four shallow channels or recesses n^{11} of the form indicated in Fig. 2. The inner parts n^{12} of the recesses n^{11} register with the arc of the openings n^9 in the arm n and are elongated lengthwise in the 95 arc of the circle which they travel in the rotation of the wheel; and the outer parts n^{13} of the recesses n^{11} extend beyond the arc of the circle described by the outer face of the reduced portion of the arm n . As before stated, 100 the arm m' is formed in every way like the arm n , and the corresponding parts thereof are given similar reference-letters in the drawings. It is to be understood that the chamber E is provided in each of its side walls with 105 recesses n^{11} the same as in each side wall of the chamber E' .

On the circumferential surface of the hub and extending in the recess i of the part D^2 of the wheel is the segment of a ring i' , which 110 abuts at one end at z , Fig. 2, against one end of the neck portion of the casting p , and at the other end abuts at z' against the other end of the neck portion of the casting p . Thus the ring i' and the neck portion of the casting p completely fill out the annular slot or opening i at the inner circumference of the chamber E' . The segment i' is of course stationary, and in the rotation of the wheel the opening i is maintained closed by the said 115 neck and segment i' . The segment i' is formed preferably of two concentric parts, the inner part i^2 being one strip the exact width of the opening i , and the other part i^3 being split longitudinally into two members i^4 , the members being serrated to afford intermeshing 120 teeth i^5 throughout part of their extent, as shown in Fig. 16. The teeth i^5 are narrower than the valves $E^2 E^3$, one of which is indi-

cated in Fig. 16, and confined in coincident sockets i^6 in the members are springs i^7 which tend to spread the members apart and press them at their outer edges yieldingly against the walls of the slots i . The intermeshing teeth need only be along those portions of the segments i' across which the valves travel when closed; and the valves being wider than the teeth no steam, should the members be slightly separated, can escape at the intermeshing edges under the valves. This construction renders the segment comparatively easy to insert into place, and when in place it forms an absolutely steam-tight packing. In the inner circumferential opening i of the chamber E is a segment of a ring i' , formed in every way like the segment described and abutting against opposite ends of the neck of the casting m . In the chamber F surrounding the shaft B is a non-rotary but longitudinally-sliding sleeve c , and in the chamber F' surrounding the shaft B is a non-rotary sliding sleeve c' . Each sleeve is provided with a tongue portion c^2 which enters a recess x^4 in the adjacent end of the body portion of the hub C. The engagement of the tongues c^2 with the recesses x^4 hold the sleeve against rotation without interfering with their longitudinally-sliding movement. On the ring c and integral therewith is an annular flange c^3 affording a shoulder and between the said shoulder and adjacent end of the sleeve the latter is provided with a screw-thread c^4 . (See Fig. 6.) Screwed upon the thread c^4 against the shoulder is a collar c^5 , which with the shoulder presents an annular recess c^6 , into which is loosely fitted a ring c^7 . The ring c^7 is provided at diametrically-opposite sides with short projecting arms c^8 , to the free ends of which are pivoted levers c^9 . At their opposite ends the levers are pivotally connected to the inner ends of radially-extending rods c^{10} , which extend through guide-openings in lugs b^3 , which are secured to or form integral parts of the wheel D. On the rods c^{10} are adjustable weights c^{11} ; also pivotally secured at one end to the rods c^{10} are levers c^{12} , which at their opposite ends are pivotally secured to arms c^{13} , extending radially from a ring c^{14} like the ring c^7 , the arms being diametrically opposite each other. Extending through an opening in the body portion of the hub parallel with the shaft B is a longitudinally-sliding rod c^{15} having a recess c^{16} , at which it loosely embraces the ring c^{14} on the inner side of the latter, and fastened at its opposite end to a lug c^{17} on the sliding sleeve c' . In each sleeve is a cam-slot c^{18} of the shape shown in detail in Fig. 7.

Journaled in the wall of the casting p and extending from the chamber F' into the chamber p^6 is a short shaft b , to the outer end of which is fixed a finger b' which extends into and engages the cam-groove c^{18} in the sleeve c' . Fixed to the inner end of the shaft b in the chamber p^6 is a swinging arm b^2 , which con-

nects at its free end with a segmental rod b^3 extending longitudinally and centrally in the chamber n^3 . (See Fig. 3.) At its opposite end the rod b^3 is pivotally connected to a frame b^4 . (Shown by plan view in Fig. 14 and in section in other figures.) The frame b^4 forms the cut-off which regulates the flow of steam from the chamber or steam-chest n^3 to the expansion-chamber E'. It comprises side bars $b^5 b^5$, an end bar b^6 , and a head or cross bar b^7 , the ends of which extend beyond the side bars b^5 . The rod b^3 is pivotally secured to the center of the head b^7 . The frame b^4 is of segmental shape, corresponding with the shape of the openings n^9 , and the side bars b^4 slide in the recesses in the forward part of the arm n which are formed by the openings n^9 where they are covered by the cap-plates n^{10} . Normally the projecting ends of the bar b^7 abut against the ends of the plates n^{10} , as when the bars $b^2 b^3$ are in the position shown in Fig. 3. When the bar b^2 is swung to the right in Fig. 3, it draws the bar b^3 and with it the frame or cut-off b^4 to reduce the size of the outlets n^9 in the manner indicated in Fig. 2. Extending through the walls of the casting m' is a short shaft b like the shaft b described, and also provided with a finger b' which enters and engages the cam-slot c^{18} in the sleeve c . The shaft b carries a rod b^2 , which connects with a rod b^3 and cut-off b^4 , Fig. 3, all constructed like the cut-off mechanism described, and in the chamber of the arm m' , to regulate the flow of steam from the said chamber to the annular expansion-chamber E. It may be stated that in the operation of the machine the ring c^7 rotates in the recess c^6 , and the ring c^{14} rotates with it in the recess c^{16} of the rod c^{15} , the levers $c^9 c^{12}$ together forming toggles at the inner ends of the rods c^{10} . The governor mechanism is so arranged that when the wheel D with the governor rotates faster than a certain speed the weighted rods are plunged outward by the centrifugal force against the resistance of the confined springs c^{19} on the rods c^{10} , spreading the toggles apart so that the sleeve c is moved to the right in Fig. 6 and the sleeve c' to the left. As the sleeves move the fingers b' are rocked by their engagement with the cam-grooves and turn the shaft b and arms b^2 , and move the rods b^3 and cut-offs in the direction of closing the outlets n^9 . Less steam being allowed to flow from the steam-chests to the expansion-chambers, as hereinafter described, the speed of the engine is reduced and the rods c^{10} are moved inward by the springs c^{19} to reverse the movement of the cut-off and increase the size of the outlets n^9 .

The operation of my improved engine is as follows: Steam enters at the passage t in the shaft B and passes thence through the opening $t' q'$ to the segmental chamber q . From the chamber q the steam passes through the outlet q^2 to the steam-chest filling the chamber therein, and the steam also passes from the chamber q through the passage q^3 and

chamber or passage p^6 to the steam-chest, filling the chamber n^3 of the latter. It is to be understood that the valves at the chamber E' close at the dotted line a in Figs. 2 and 3 5 and open at the dotted line a' in those figures. In other words, the valves in the expansion-chamber E' each close just in front of the forward end of the arm or steam-chest n and open just before they reach the head p . 10 The steam-chest m' at the chamber E is diametrically opposed to the steam-chest n , so that in the chamber E the valves close on the line a' and open on the line a , the opening and closing of all the valves being effected, as 15 before described, by the movement of the antifriction-wheels $g^4 f^5$ upon the inner and outer cams $h h'$. Presuming that the parts n^{12} of one set of recesses n^{11} , which are in the same 20 relative positions, register with the outlets n^9 of the steam-chest, and that a valve E^3 is closed on the line a in the chamber E', and a valve E^2 is closed on the line a' in the chamber E, steam from the steam-chest will pass out at n^9 into the parts n^{12} of the respective 25 recesses n^{11} and through the parts n^{13} of said recesses into the chambers formed by the spaces on the inner and outer sides of the arms or chests $n m'$ and closed at one end by the stationary abutments or shoulders n^8 and 30 at their opposite ends by the closed valves carried by the wheel D. The pressure of the steam against the closed valves causes the wheel D to rotate on its bearings $x^3 k$, the flow of the steam from the steam-chest being cut 35 off as soon as the recesses n^{11} pass the outlets n^9 , whereby the expansive force of the steam is utilized after it is cut off from the source of supply. When the wheel has rotated a quarter-revolution a second valve closes in 40 front of the steam-chest in each chamber and the next recesses n^{11} register with the outlets n^9 of the steam-chest. As the wheel nears a half-revolution the first-mentioned valve E^3 45 passes at its inner peripheral edge over the circumferential opening p^5 in the casting p , thereby opening the chamber between the said valve E^3 and the next following valve to the exhaust through $p^5 e^2$ to the segmental chamber e in the hub, whence the steam ex- 50 hausts through the passage $e' s'$ to the exhaust-passage s in the shaft B. At the same time the first said valve E^3 in the chamber E as the wheel nears a half-revolution passes across an outlet-opening in the casting m 55 corresponding with the outlet p^5 , and which forms the mouth of the passage e^3 in the hub leading to the exhaust-chamber e . The operation is continuous, each temporary segmental chamber in the annular chambers E 60 E' being open to pressure in the first quarter-revolution of the wheel and open to exhaust in the second quarter-revolution of the wheel. As the valves are passing the exhaust-opening in the chambers E E' they open to clear 65 the heads $p m$. The speed of rotation of the wheel D is regulated by the governor and cut-off mechanism before described.

I prefer to fill the chambers F F' to a level corresponding, say, with the under side of the trunnions D³ with lubricating-oil, and this 70 will provide all lubrication required for the engine. The rotation of the wheel will keep the oil splashing against the sides of the hub to lubricate the bearing-surfaces $x^2 x^3$ and against the shaft B; and the trunnions D³ and 75 hubs of the cams are provided with oil-channels a^2 and the shaft with channels a^3 to conduct the oil to lubricate the trunnions at the bearings k . By means of the rings $d d^4$, diametrically-opposed valves E² and E³ are tied 80 together against centrifugal force and they are thus caused to slide without material friction. This means of balancing the valves is one of the more important features of my 85 improvement.

In the rotation of the wheel the walls of the chambers E E' before reaching the steam-outlets n^9 pass across the chambered heads $p m$, which, being maintained at a high temperature by the live steam which passes through 90 them, heat the inner surfaces of the walls of the expansion-chamber. Thus the steam flowing from the outlets n^9 meets heated surfaces, and any tendency to condensation of the steam during the period of admission to and 95 expansion in said chambers is prevented. The heat from the heads $m p$ keeps the walls of the chambers E E' always at a high temperature, renewing, before they reach the steam-outlets n^9 , any heat they may have lost 100 between the time that they pass the forward ends of the steam-chests and reach the heads. This is also one of the important features of my invention, because hitherto loss of heat by radiation through the walls of the expansion-chambers has had a tendency to cause 105 the steam at the time of admission and expansion to condense to a more or less extent and cause loss of steam to a very material extent. 110

It is to be understood that I do not confine myself to the particular construction of governor mechanism shown and described; nor do I confine my improvements to a double engine like the one shown, because they are 115 equally applicable to engines employing but one expansion-chamber or engines employing more than two expansion-chambers.

It will readily be seen that were the wheel D fastened in a manner to prevent its rotation and the shaft B with its attendant parts mounted in bearing to rotate, the engine, with slight modifications which would suggest themselves to any skilled mechanic, would operate equally as well. In such case, of 120 course, a pulley or analogous power-transmitter could be mounted upon the shaft instead of upon the, what would then be, stationary wheel or shell portion D.

Although my improved engine is intended 125 for the employment of steam as a motive power, air from a compressed air-supply or other fluid under pressure could be employed in place of steam. The term "steam" where

employed in the claims is intended to embrace any power-supplying fluid which would be the equivalent of steam in furnishing the motive power.

5 By having the steam-chest form the abutment in the expansion-chamber, the mechanism is of course simplified. However, if desired, the abutment and steam-chest could be separate as well as the means for raising the 10 temperature of the expansion-chamber wall prior to the admission of the steam from the steam-supply. If desired, therefore, a chambered head separate and distinct from the steam-supply could be provided in the expansion-chamber adjacent to the supply-port to be heated by a separate supply of steam from that which is employed in propelling the moving parts. My claims are intended to cover such modification.

20 While I prefer to construct my improvements as shown and described, they may be modified in the matter of details of construction without departing from the spirit of my invention as defined in the claims.

25 What I claim as new, and desire to secure by Letters Patent, is—

1. In a rotary engine the combination of a shell provided with an annular expansion-chamber, an abutment extending across said 30 chamber, the shell and abutment therein being so supported with relation to each other that one is stationary and the other rotates, a steam-inlet and a steam exhaust at said chamber, laterally sliding valves in opposite sides 35 of the chamber, reciprocal rods on which said valves are mounted the ends being tied together and reciprocating means for the rod operating in the movement of the rotary parts of the engine to move the valves simultaneously in the same direction, substantially as 40 and for the purpose set forth.

2. In a rotary engine, the combination of a shell provided with an annular expansion chamber, an abutment extending across said chamber, the shell and abutment therein being so supported with relation to each other that one is stationary and the other rotates, a steam inlet and a steam exhaust at said chamber, laterally sliding valves in opposite sides 45 of the chamber, the valves being tied together to move in the same direction simultaneously and so arranged with relation to each other and to the chamber, that, in their movement, one opens while the other closes, and means, 50 actuated by the movement of the rotary parts of the engine, for moving said valves, substantially as and for the purpose set forth.

3. In a rotary engine the combination of a shell provided with an annular expansion 60 chamber, an abutment extending across said chamber, the shell and abutment therein being so supported with relation to each other that one is stationary and the other rotates, a steam inlet and a steam exhaust at said chamber, laterally sliding valves in opposite sides 65 of the chamber, reciprocal rods on which said valves are mounted, yokes connecting said

rods whereby they move together and slide the valves in the same direction simultaneously, and means, actuated by movement of 70 the rotary parts of the engine, for moving the said rods with the yokes and valves, substantially as and for the purpose set forth.

4. In a rotary engine, the combination of a shell provided with an annular expansion 75 chamber, an abutment extending across said chamber, the shell and abutment therein being so supported with relation to each other that one is stationary and the other rotates, a steam inlet and a steam exhaust at said chamber, laterally sliding valves in opposite sides 80 of the chamber, reciprocal rods on which said valves are mounted, the rods being tied together to move simultaneously in the same direction, and cams at the ends of the rods operating in the movement of the rotary parts of the engine to reciprocate the rods and open and close the valves, substantially as and for the purpose set forth.

5. In a rotary engine a shell provided with 90 an annular expansion chamber, laterally sliding valves in opposite sides of the chamber and reciprocating rods on which said valves are mounted, the rods being tied together to move simultaneously in the same direction, 95 in combination with a shaft provided with a hub carrying an abutment extending across said chamber, annular cams at the ends of the reciprocal rods for moving the same, the shell with the parts carried thereby and the shaft 100 with the parts carried thereby being so supported with relation to each other that when one, with the parts carried thereby, is stationary, the other, with the parts carried thereby, rotates, and a steam inlet and a steam exhaust 105 at said chamber, substantially as and for the purpose set forth.

6. In a rotary engine, the combination of a shell provided with an annular expansion chamber, lateral recesses at diametrically opposite sides of the said chamber, the recesses extending respectively in opposite directions from the said chamber, sliding valves at the said recesses and movable into the recesses to open the chamber and out of the recesses to 110 close the chamber and form approximately steam tight abutments therein, longitudinally reciprocal rods on which the said valves are mounted, yokes tying the rods together whereby they move with the valves simultaneously in the same direction to cause one said valve to open and the other to close, an abutment extending across said chamber, the shell and abutment therein being so supported with 115 relation to each other that one is stationary and the other rotates, a steam inlet and a steam exhaust at the said chamber, and actuating means for the rods, mounted in fixed relation with the said abutment, and operating in the movement of the rotary parts of 120 the engine to shift the yokes, rods and valves, substantially as and for the purpose set forth.

7. In a rotary engine, the combination of a shell provided with an annular expansion

chamber, laterally sliding valves at diametrically opposite sides of the said chamber movable respectively into and out of the said chamber from opposite directions, yokes laterally and at opposite sides of the said chamber, reciprocal rods to which the valves are fastened extending across the shell and secured at their opposite end portions to the said yokes whereby the valves are tied together to move simultaneously in the same direction, a shaft, an abutment in fixed relation to the shaft extending across the said chamber, cams at the ends of the said rods mounted in rigid relation with the shaft, the shell, valves and yokes on the one hand, and the shaft, abutment and cams, on the other hand, being so supported with relation to each other that one is stationary and the other rotates, the cams operating in the movement of the rotary parts to reciprocate the valves, and a steam inlet and a steam exhaust at said chamber, substantially as and for the purpose set forth.

8. In a rotary engine, the combination of a shell provided with an annular expansion chamber, laterally sliding valves at diametrically opposite sides of the said chamber movable respectively into and out of said chamber from opposite directions, reciprocal rods *g* extending across the shell and fastened to the said valves, rods *f* parallel with the rods *g*, yokes laterally and at opposite sides of the expansion chamber connecting all said rods together whereby they move with the valves simultaneously in the same direction, a shaft, an abutment in rigid relation with the shaft and extending across said chamber, inner and outer cams *h* *h'* at opposite ends of the said rods, the shell, valves, rods and yokes, on the one hand, and the shaft, abutment and cams, on the other hand, being so supported with relation to each other that one is stationary and the other rotates, and the cams being so disposed with relation to each other and to the rods that the inner cams each engage an end of one of the rods *g* and the outer cams each engage an end of one of the rods *f* and operate in the movement of the rotating parts of the engine to shift the valves, and a steam inlet and a steam exhaust at said chamber, all constructed and arranged to operate substantially as described.

9. In a rotary engine, the combination of a shell provided with an annular expansion chamber, an abutment extending across said chamber and provided in opposite sides adjacent to the chamber wall with steam supply ports, the shell and abutment therein being so supported with relation to each other that one is stationary and the other rotates, steam channels in opposite sides of the chamber operating in the movement of the rotating parts to register intermittently with the steam supply port to open the same to the chamber, valves at the said chamber, means for moving the valves operating to open them at one side of the abutment and close them

at the opposite side thereof, and an exhaust for the chamber, substantially as and for the purpose set forth.

10. In a rotary engine the combination of a shell provided with an annular expansion chamber, an abutment extending across said chamber and provided in a side adjacent to the chamber wall with a steam supply port, the shell and abutment therein being so supported with relation to each other that one is stationary and the other rotates a governor-controlled cut-off at said port, steam channels in the chamber operating in the movement of the rotating parts to register intermittently with the steam inlet to open the same to the chamber, sliding valves at the said chamber, means for moving the valves operating to open them at one side of the abutment and close them at the opposite side thereof, and an exhaust for the chamber, substantially as and for the purpose set forth.

11. In a rotary engine, the combination of a shell provided with an annular expansion chamber, a steam chest having an enlarged portion which fills out and forms an abutment in said chamber, and a reduced portion in contact at one side at least with one wall of the chamber, and there provided with a steam supply port, and out of contact, at least at one other side, with the respective adjacent wall of the chamber, the shell and steam-chest being so supported with relation to each other that one is stationary and the other rotates, a steam channel, in the wall of the chamber, with which the said port registers intermittently in the movement of the rotating parts to conduct steam from said port into the chamber, sliding valves at said chamber, means for moving the valves operating to open them at one end of the steam-chest and close them at the opposite end thereof, and an exhaust for the chamber, substantially as and for the purpose set forth.

12. In a rotary engine, the combination of a shell provided with an annular expansion chamber, a steam-chest in said chamber having a head-portion provided with expandible packing-strips to fill out the said chamber and a reduced portion in contact at one side at least with one wall of the chamber, and there provided with a steam supply port, and out of contact, at least at one other side, with the respective adjacent wall of the chamber, the shell and steam-chest being so supported with relation to each other that one is stationary and the other rotates, a steam channel, in the wall of the chamber, with which the said port registers intermittently in the movement of the rotating parts to conduct steam from said port into the chamber, sliding valves at the said chamber, means for sliding the valves operating to open them at one end of the steam chest and close them at the opposite end thereof, and an exhaust for the chamber, substantially as and for the purpose set forth.

13. In a rotary engine, the combination of a shaft, a hub upon the shaft, an annular ex-

- 5 pansion chamber extending about the hub and having an annular inner circumferential opening, a steam-chest in fixed relation to the hub, a steam-supply passage through the shaft and hub to the steam-chest, a steam-exhaust passage from the annular chamber through the hub and shaft, the steam-chest comprising a neck-portion passing through said annular slot, a head portion filling out the said chamber and forming an abutment therein, and a reduced portion contacting at one side with the wall of the chamber and there provided with a steam supply port, the shell, on the one hand, and the shaft, hub and steam-chest, on the other hand, being so supported with relation to each other that one is stationary and the other rotates, a segmental packing-strip in said annular slot abutting at opposite ends against the neck-portion of the steam-chest, a steam channel in a side of the chamber to register intermittently with the steam supply port, and valves in said chamber provided with means for operating them, substantially as and for the purpose set forth.
- 10 14. In a rotary engine, a shell provided with two annular expansion chambers, an abutment extending across each said chamber, the shell and abutments therein being so supported with relation to each other that one is stationary and the other rotates, a steam-inlet and a steam-exhaust at each said chamber, valves in opposite sides of the chambers tied together to move simultaneously in the same direction and means for actuating the valves whereby they move in both said chambers simultaneously, substantially as and for the purpose set forth.
- 15 15. In a rotary engine, the combination, with the annular expansion chamber, of the steam-chest therein having a head-portion provided with circumferential grooves n^2 , openings from said grooves to the chamber of the steam-chest, movable pins filling out said openings and packing-strips resting in said grooves against the ends of the pins, substantially as and for the purpose set forth.
- 20 16. In a rotary engine, the combination of the shaft and hub-portion thereon having an annular bearing surface and provided with steam-inlet and exhaust passages, an annular shell containing an annular expansion chamber, an annular inner peripheral slot and an annular inner peripheral bearing-surface fitting the bearing surface of the hub, an abutment in the chamber mounted in fixed relation to the hub and containing a steam-chest communicating with the said steam-inlet passage and having a steam supply port and an exhaust opening at said abutment communicating with the said exhaust passage, a segmental packing-strip on the bearing surface of the hub fitting into the annular slot of the shell and abutting at opposite ends against opposite sides of said abutment, the abutment having a hollow neck-portion which fits the slot and with the said packing-strip forms a steam-tight packing for the slot, the shell,
- 25 on the one hand, and the hub and abutment, on the other hand, being so supported with relation to each other that one is stationary and the other rotates, means actuated by movement of the rotating parts to open and close said chamber, and intermittently actuating means operating in the rotation of said moving parts to open and close the steam-supply port from the steam-chest to the expansion-chamber, substantially as and for the purpose set forth.
- 30 17. In a rotary engine, the combination of a shell provided with an annular expansion-chamber, an abutment extending across said chamber, the shell and abutment therein being so supported with relation to each other that one is stationary and the other rotates, a steam-chest at said abutment having a steam-supply port, an exhaust for the chamber, valves at said chamber, valve-actuating mechanism operating in the movement of the rotating parts to open the valves behind said abutment and close them in front thereof, and means operating in the movement of the rotating parts to open the said steam-supply port to the chamber on the closure of a valve and then close said port, whereby the expansive force of the steam is utilized after the steam is cut off from its source of supply, substantially as described.
- 35 18. In a rotary engine, the combination with the shell having an annular inner bearing-surface, annular expansion-chamber, and an annular slot in said bearing-surface, hub provided with a circumferential bearing surface for the said bearing-surface of the shell, head on the hub having a neck portion fitting through said slot, enlarged portion filling out said chamber and containing the steam-chest, of a segmental packing-strip on the bearing surface of the hub extending into said slot and abutting at opposite ends against opposite sides of the said head, the packing-strip comprising inner and outer concentric sections, one of said sections being laterally expansible, substantially as described.
- 40 19. In a rotary engine, the combination with the shell having an annular inner bearing surface, annular expansion chamber, and an annular slot in said bearing surface, hub provided with a circumferential bearing surface for the said bearing surface of the shell, head on the hub having a neck-portion fitting through said slot, an enlarged portion filling out said chamber and containing the steam chest, of a segmental packing-strip on the bearing surface of the hub extending into the said slot and abutting at opposite ends against the sides of the said head, the packing-strip comprising inner and outer concentric sections, one of which consists of two parallel members serrated at adjacent edges to intermesh, substantially as and for the purpose set forth.
- 45 20. In a rotary engine, the combination with the shell provided with an annular expansion chamber, valves in said chamber and steam-

chest extending across said chamber and so mounted with relation to the shell that one is stationary and the other rotates, of one or more steam-supply ports in the steam-chest 5 comprising each a segmental opening, a steam channel in the shell for each said supply port operating in the rotation of the moving parts to register intermittently with the respective port and conduct steam therefrom to the 10 chamber, of a governor-actuated sliding cut-off at the ports for enlarging and reducing the same, substantially as and for the purpose set forth.

21. In a rotary engine, the combination of a 15 shell containing two or more annular expansion chambers provided with valves, and a hub having a steam-supply chamber, two or more steam-chests extending into and forming abutments in the said expansion-chambers and communicating with the said steam-supply chamber, a steam supply port in each steam-chest, an exhaust chamber in the hub, 20 passages in the hub extending from said exhaust chamber to the said expansion chambers, the hub and shell being so supported with relation to each other that one is stationary and the other rotates, and means operating in the rotation of the moving parts to 25 actuate the valves and open and close the supply ports from the steam-chests to the expansion chambers, all constructed to operate substantially as and for the purpose set forth.

22. In a rotary engine the combination of a 30 shell having an annular expansion-chamber, an abutment extending across said chamber, the shell and abutment therein being so supported with relation to each other that one is stationary and the other rotates, a steam inlet and a steam exhaust at said chamber, 35 opening and closing valves at the chamber provided with means for operating them in the rotation of the moving parts and a heater 40

in said chamber operating to raise the temperature of the chamber walls just before they contact with steam from the said steam inlet, 45 substantially as and for the purpose set forth.

23. In a rotary engine, the combination of a shell provided with an expansion-chamber, an abutment extending across said chamber, the shell and abutment therein being so supported with relation to each other that one is stationary and the other rotates, a steam inlet and a steam exhaust at said chamber, 50 opening and closing valves at said chamber with means for operating them in the rotation of the moving parts, and a hollow head in said chamber in fixed relation with the said abutment and communicating with a steam supply, the head operating to heat the walls of the expansion-chamber before they contact 55 with the steam from the steam inlet, substantially as and for the purpose set forth.

24. In a rotary engine the combination of a relatively stationary shaft provided with steam inlet and exhaust passages, rotary shell 60 about the said shaft containing an annular expansion chamber provided with steam inlet and exhaust ports, opening and closing valves in the said chamber with means for operating them, supporting means for the shaft and 65 means for holding the said shaft against rotation comprising a block r^3 fixed to the shaft, a block r^2 in which the block r^3 is mounted to slide in one direction and a support in which the block r^2 is mounted to slide in the direction at right angles to the said movement of the block r^3 , the support operating to hold the block against rotation, substantially as described. 70
